UNITED STATES PATENT OFFICE

HARRY M. PFLAGER, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

TENDER STRUCTURE

Application filed February 11, 1928. Serial No. 253,637.

My invention relates to railway rolling stock and consists in novel construction of locomotive tenders, and particularly in the formation of the underframe which is adapted to form a part of the tender tank structure. In the copending application Serial No. 202,877, filed July 1, 1927, by William O. Ashe and myself, there is illustrated a tender underframe casting adapted to form the bottom of a rectangular tank, the side and end sheets of which are welded or riveted to the underframe structure.

The main object of my present invention is to provide an underframe for a cylindrical tank and to assemble the tank superstructure therewith in such manner as to provide for maximum capacity, for the lowest possible center of gravity and with the use of a minimum amount of material for the required strength.

In the preferred embodiment of my invention, the underframe is located on the interior of the tank cylinder substantially throughout the entire length of the latter and the underframe structure forms a portion of the tank wall.

Various detailed objects of my invention are concerned with the suitable construction of a vehicle having the above features, as will be referred to in my detailed specification.

In the accompanying drawings which illustrate my invention—

Figure 1 is a top view of one longitudinal half of my underframe, duplicate parts being eliminated.

Figure 2 is a vertical section along the longitudinal center line of the underframe.

Figures 3, 4, 5, 6, and 7, are vertical transverse sections taken on the lines 3—3, 4—4, 5—5, 6—6, and 7—7, of Figures 1 and 2.

Figure 8 is a side elevation of a complete tender mounted on my improved underframe.

Figures 9 and 10 are elevations of the front and rear ends, respectively, of the underframe.

Figure 11 shows on the left a vertical transverse section taken on the line 11—11 of Figure 8, and shows on the right a similar section taken on line 11a—11a of Figure 8.

Figures 12 and 12a are vertical transverse sections illustrating modifications of my invention.

Figure 13 is a fragmentary top view of one end of a modified form of underframe. 55

Figures 14 and 15 are vertical transverse sections taken on lines 14—14 and 15—15 of Figure 13.

Figures 16 and 17 are vertical longitudinal sections on line 16—16 and 17—17 of Figure 13. 60

Figure 18 is a fragmentary top view illustrating another modified underframe.

Figures 19, 20, and 22, are vertical transverse sections taken on lines 19—19, 20—20, 65 and 22—22 of Figure 18.

Figure 21 is a similar section through the air brake bracket which is not shown in Figure 18.

The underframe casting, which also forms 70 a part of the tank structure, comprises spaced longitudinal sill elements 1, connected by a lower horizontally disposed web 2 and an upper horizontally disposed web 3, all forming a box-shaped center sill and extending substantially throughout the length 75 of the underframe. Between the left hand bolster 4 and the corresponding end sill 5, the lower web 2 is inclined downwardly and offset upwardly, as indicated at 6, to accommodate any ordinary draft rigging arrangement. The opposite end of the lower web 2 merges with elements 7 and 8 to form a pocket for a connecting bar. An outwardly 80 extending flange 9 is provided along the lower portion of each sill element 1 and these flanges have finished pads on their upper faces for mounting the lower edges of superstructure sheets 10, preferably curved to form the upper portion of a cylindrical 85 tank.

At the bolster, the lower web 2 is extended upwardly and outwardly to form side bearings 11 and the upper web 3 is extended laterally to form the top wall 12 of a box-shaped bolster structure and terminates in an upwardly inclined flange 13 to which the superstructure sheets 10 may be secured. At the center of the bolster a suitable center plate mounting element 14 is provided and 90 95 100

this portion of the bolster is reenforced by additional vertical webs 15 which may be arranged as shown in Figure 1 or in any other desired form.

Intermediate the bolsters the lower web 2 is extended outwardly, as indicated at 16 (Figure 3), to form a bracket for mounting a brake cylinder or other similar apparatus and a horizontally extending flange 17, terminating in a pad 18, is provided above bracket 16 for mounting the tank sheets 10 and for providing access to the attaching bolts passing through bracket 16.

In Figure 11, I illustrate the manner in which reenforcing braces 19 may be applied to the underframe and to the tank sheets and it will be understood that where these braces are to be attached to the underframe, the latter will be provided with suitable pads which may be machined in order to form a bearing. Splash sheets 20 may be secured to braces 19 in the usual manner.

The longitudinal sill elements 1, and other vertical walls in the underframe, are perforated, where necessary, as indicated at 21, to provide for free passage of water from one part of the tank structure to the other.

The end sheets of the tank may be riveted or welded to suitable pads, as indicated at 22 at the left hand end of Figure 2, or these sheets may be attached to the pad by means of connecting angles 23, as indicated at the right hand end of Figure 2.

The construction shown provides a continuous horizontally disposed flange extending throughout the length of the underframe and adapted to mount the tank superstructure sheets, and where the frame necessarily includes transversely extending portions, as at the bolsters 4, brake cylinder brackets 16, and end sills 5, the flange is extended transversely of the frame along the arc of the tank wall. The flange on the inner end sill wall is indicated at 40 (see Figure 7). This flange avoids the provision of recesses in the tank sheets to permit them to receive the laterally projecting members and avoids the provision of additional connection members between the edges of recesses in the tank sheets and such members which would be a more difficult and expensive construction.

The structure illustrated makes possible the use of a light underframe because the underframe forms a part of the tank and does not have to carry a complete tank superstructure and the tank side sheets extend into the center sill members instead of the underframe extending out to the sides of the tank. The center of gravity of the entire structure is lower than in those tenders where a complete tank is carried on the underframe and is even lower than in the above mentioned application, where the tank superstructure

plates are secured to the upper portion of the underframe.

The advantages of the construction described above are retained in the modifications of my invention which show various arrangements for securing similar results, for instance, in that illustrated in Figures 12 and 12a, the bolster bottom web 24 terminates adjacent to the side bearing 41 and is there provided with an inclined flange 25 for mounting the tank sheet 26, the outer portions of the upper web 27 and the lower web 24 being connected by a suitable web 28. Similarly, the air cylinder bracket 29 is provided with an upstanding web 30 and an inclined flange 31 to which the superstructure sheet may be attached.

In the construction shown in Figures 13 to 17, inclusive, the tank superstructure plates 32 are attached to the flange 33 of the underframe between the bolsters 34 only and between the bolsters and the end sills 40 the tank sheets are fastened to the top of the underframe casting, either directly or by means of connecting angles. In order to accommodate this construction, vertical plates 35 and suitable connecting angles 36 are utilized where necessary.

In the construction shown in Figures 18 to 22, inclusive, a member having a sheet attaching flange 37 is provided between the level of the upper and lower portions of the center sill 38 and this member extends in a straight line between the end sills and is spaced from the center sill. This construction eliminates the curved flanges on the sides of the bolsters and other laterally extending members as required in the preferred construction and also avoids any shaping of the longitudinally extending superstructure sheets of the tank. The tank end sheets may be secured to suitable pads 39 and may be recessed along their lower edges to follow the contour indicated in Figure 22.

The box section center sill which I have illustrated in my drawings and the one piece casting structure are not essential to the embodiment of my invention, as spaced center sills of channel shape or I beam cross section may be utilized and connected, either by integral webs, if a casting is used, or by suitable plates welded or riveted to the sill elements.

These and other variations in the details of construction may be made without departing from the spirit of my invention, and I contemplate the exclusive use of all such modifications as come within the scope of my claims.

I claim:

1. A railway vehicle longitudinal sill member extending from end to end of the vehicle and having a lateral flange spaced below the top thereof and curved upwardly to mount a cylindrical tank superstructure sheet.

2. A railway vehicle sill member extending from end to end of the vehicle having an outwardly and upwardly curved flange near its lower portion and adapted to mount a tank superstructure sheet. 5
3. A railway vehicle hollow box shape longitudinal sill member having means spaced below the top thereof for mounting the lower edge of a tank superstructure sheet. 10
- 10 4. A railway vehicle underframe longitudinal sill of four sided box-shaped cross section and adapted to mount the lower edges of tank superstructure sheets below its top and adapted to contain liquid substantially 15 throughout its width and depth. 15
5. A railway vehicle four sided box-shaped longitudinal sill member having means spaced below the top thereof for mounting the lower edge of a tank superstructure sheet. 20
- 20 6. In a railway tank vehicle, a longitudinal sill of four sided box-shaped cross section and adapted to mount the lower edges of tank superstructure sheets at the lower portions of its sides so as to position said sill substantially wholly above the tank bottom and to form a liquid chamber between the side walls of said sill and above said lower edges. 25
7. In a railway vehicle, a box-shaped longitudinal sill with an imperforate bottom wall and with outwardly extending flanges at its lower sides, and sheets forming the lower portion of a cylindrical tank and having their lower edges secured to said flanges. 30
- 35 8. In a railway vehicle underframe, spaced longitudinal sill members, a web between the lower portions of said members forming therewith a liquid container, and elements on said members, spaced from the top thereof, for mounting tank superstructure sheets. 40
9. In a railway vehicle underframe, spaced longitudinal sill elements and a web between the lower portions of said elements, said elements and web forming a receptacle adapted 45 to contain liquids, and means on the lower exterior portion of said receptacle for mounting tank superstructure sheets. 45
10. In a railway vehicle underframe, end sills, a longitudinal sill member between said 50 end sills, an element on the lower portion of said longitudinal sill member for mounting tank side sheets, and elements extending inwardly from said end sills and at the top of said longitudinal sill member for mounting tank end sheets. 55
11. In a vehicle underframe, end sills, spaced longitudinal sill members between said end sills, elements on the lower portion of said longitudinal sill members for mounting tank side sheets, and elements extending inwardly from said end sills and at the top of said longitudinal sill members for mounting tank end sheets. 60
12. In a railway vehicle underframe, an 65 end sill, and a flange on the rear of said sill adapted to be connected to tank side and end sheets, said flange extending from the lower portion of said sill at points near the longitudinal center line of said underframe to the top portion of said sill at the ends thereof. 70
13. In a railway vehicle underframe, end sills, bolsters, a longitudinal sill member, elements located on the rear of said end sills and on the sides and ends of said bolsters and on the sides of said longitudinal sill member for mounting tank sheets so as to position said longitudinal sill member substantially 75 wholly above the tank bottom. 75
14. In a railway vehicle underframe, bolsters spaced from the ends of the underframe, flanges on the sides of said bolsters adapted to be connected to tank side sheets, said flanges extending from the lower portion of said bolster near the longitudinal center line of said underframe to the top portion of the 80 ends of said bolsters. 80
15. In a railway vehicle underframe, a longitudinal sill member, a brake cylinder bracket extending from the side thereof, and flanges on the sides of said bracket adapted to 90 mount a tank side sheet, said flanges extending from the lower portion of said bracket nearest the longitudinal center line of the underframe to the top portion of the end of said bracket. 95
16. In a railway vehicle, an underframe casting including spaced longitudinal sill members and a web extending between the lower portions of said members, and tank superstructure sheets secured to the lower 100 portions of said members and with said web forming a continuous tank wall. 100
17. In a railway tank vehicle, an underframe having end sills and spaced longitudinal sill members, a cylindrical tank extending between said end sills, the side sheets of said tank being connected to the lower portion of said longitudinal sill members, and the end sheets of said tank being connected to said end sills and to the top and 105 sides of said longitudinal sill members. 110
18. In a railway tank vehicle, an underframe having end sills and a longitudinal sill member, said member between said end sills forming a portion of a tank and adapted to contain liquids, a cylindrical tank extending between said end sills, the side sheets of said tank being connected to the lower portion of said longitudinal sill and the end sheets of said tank being connected to said end sills and to the top and sides of said longitudinal 115 sill. 120
19. In a railway tank vehicle, end sills, bolsters, spaced longitudinal sill members, elements located on the rear of said end sills and on the sides and ends of said bolsters and on the sides of said center sill members for mounting tank sheets so as to position said longitudinal sill members substantially wholly above the tank bottom. 125 130

20. In a railway vehicle, an underframe casting having a box section longitudinal sill, sheets forming a cylindrical tank and connected directly to the lower portion of said sill, and tank braces extending to the lower portion of said sill and connected to said sill and to said sheets.
21. In a railway vehicle, an underframe, curved sheets forming the sides of a tank, bolsters spaced from the ends of the underframe, flanges on the sides of said bolsters adapted to mount said sheets, said flanges extending from the lower portion of said bolster near the longitudinal center line of said underframe to the end of said bolster and said flanges having the same contour as said sheets.
22. In a railway vehicle underframe, an end sill, and a flange on the rear of said sill adapted to be connected to tank side and end sheets, said flange extending from the lower portion of said sill, at points near the longitudinal center line of said underframe, to the ends of said sill, and said flange having the same contour as said side sheets.
23. In a railway tank vehicle, an underframe including a longitudinal sill and a laterally extending air brake cylinder bracket, and superstructure tank sheets secured to said bracket.
24. A railway tank vehicle underframe having a longitudinal sill and a laterally extending brake cylinder bracket adapted to form a portion of a tank wall.
25. In a railway tank vehicle, end sills, a cylindrical tank and a longitudinal sill member, both extending between said end sills, the lower portion of which sill member is adapted to support the lower edges of the tank sheets so as to position said member substantially wholly above the bottom of the tank.
26. A railway vehicle underframe including a longitudinal sill from end to end of the underframe and comprising a box-shaped cross section with flanges on its lower exterior portion for mounting tank superstructure sheets.
27. In a railway cylindrical-tank vehicle, a longitudinal rigid underframe member extending the full length of said vehicle and forming the bottom of the tank, and tank superstructure side sheets extending in an arc to the bottom of said members and terminating in spaced edges secured to said members.
28. A railway vehicle sill member having an outwardly and upwardly curved flange extending from its lower end portion and adapted to mount a cylindrical tank superstructure sheet.
29. In a railway vehicle underframe, end sills, a longitudinal sill member extending between said end sills and adapted to form a portion of a tank bottom, and means on the lower portion of said member for mounting tank side sheets.
30. In a railway vehicle underframe, spaced longitudinal sill members extending throughout the length of the underframe, a horizontal web between said members spaced below the top of the same and forming therewith a liquid container, and elements on said members, spaced below the top thereof, for mounting tank superstructure sheets.
31. In a railway vehicle underframe, spaced longitudinal sill elements and a web between the lower portions of said elements, said elements and web forming a receptacle adapted to contain liquid, and means on the lower exterior portion of said receptacle for mounting tank superstructure sheets.
32. In a railway vehicle, end sills, a cylindrical tank superstructure extending substantially from end sill to end sill, and a centrally located longitudinal sill extending between said end sills, the lower portion of said tank superstructure being secured directly to said longitudinal sill.
- In testimony whereof I hereunto affix my signature this 10th day of January, 1928.
- H. M. PFLÄGER.
